HOSE SUPPORTER BUTTON AND BASE PLATE

Irving R. Versoy, New Haven, Conn., assignor to
The Berger Brothers Company, New Haven,
Conn., a corporation of Connecticut

Application May 20, 1935, Serial No. 22,293

4 Claims. (Cl. 24—245)

This invention relates to grips for hose supporters or the like, and more particularly to the construction of the base plate upon which is supported the usual button which cooperates with a metallic loop to grip the stocking so as to secure it to the supporter.

It has been more or less common practice in hose supporter grips of this character to provide a base plate to support the button, the latter being secured to the base plate by any suitable means such as by a rivet passing through the button and the plate. This plate is ordinarily formed of sheet metal and is substantially flat, all parts thereof lying in the same plane. In the usual method of securing the stocking, the latter is passed over the button and therefore lies above the base plate. As this member is flat, the edges do not conform to the leg of the wearer but project outwardly to some extent from the surrounding parts of the leg and the stocking is thus drawn tightly over the relatively sharp edges of the plate. This results in damage to the stocking such as the production of a tear or run.

One object of the present invention is to overcome the disadvantages referred to above and to provide a hose supporter grip having a base plate which will closely conform to the leg of the wearer.

Another object of the invention is the provision of a base plate for supporting a hose supporter button so arranged that the side edges of the plate will extend in a generally downward direction so as not to cut into or damage the stocking lying above the plate. More particularly the invention resides in the provision of a base plate of convex shape along its transverse dimension, with the convex side of the plate facing upwardly or toward the hose supporter button, so that the edges of the plate will not project in a lateral direction to cut into the stocking of the wearer.

To these and other ends the invention consists in the novel features and combination of parts to be hereinafter described and claimed.

In the drawing:

Fig. 1 is a front elevational view of a hose supporter provided with my improvements;

Fig. 2 is an end elevational view looking in the direction of the arrow 2 on Fig. 1;

Fig. 3 is an end elevational view of the hose supporter button and supporting plate;

Fig. 4 is a top plan view of the parts shown in Fig. 3; and

Fig. 5 is a sectional view on line 5—5 of Fig. 3.

To illustrate a preferred embodiment of my invention, I have shown a hose supporter comprising the usual elastic webbing 10 to the lower end of which is attached an upper loop 11 to which is secured a lower loop 12, usually made of metal. As is the usual custom, and as shown in the present drawing, this lower loop is provided with a reduced portion 13 at its lower end designed to receive the shank 14 of a button having an enlarged top 15. While the width of the lower portion 13 of the metal loop 12 will slidably receive the shank 14 of the button, the head 15 is too large to be drawn through this portion of the loop.

The button may be formed in any desired manner and of any desired material, but preferably both the head 15 and shank 14 may be made of rubber or some soft material, and secured by means of a rivet 16 to a base plate designated generally by the numeral 17.

This base plate is preferably formed of sheet metal and is provided with upper and lower slots 18 and 19. Upon its sides or lateral edges the metal may be recessed or cut out, as shown at 20, so that the portions of the plate at the ends 25 of the slots 18 and 19 appear more or less as projecting corners.

The base plate and button are usually secured to the loop 11 by means of a piece of fabric 21 which is looped about a portion of the part 11 30 and having one end passed below the plate 17 and turned upwardly about the lower end of the plate and threaded through the slot 19. This end of the fabric is then brought upwardly below the button and below the central part of the base 35 plate to which the button is secured, and brought out through the upper slot 18, where the ends of the fabric 21 are joined, such as by stitching, as shown at 22. It will be apparent that the fabric portion 21 when threaded in this manner 40 lies below the metal base plate 17.

In the usual form the metal base plate is of substantially plane shape, and it will be apparent that whether or not the cut-out or recessed portions 20 are provided, the lateral edges or corners 45 of this plate will, when the supporter is worn, stand in a position more or less raised from the wearer's body. That is, if the central portion of the plate below the button 15 is rested upon the leg, the side edges of the plate will project laterally and not lie closely against the leg of the wearer. By the side edges of the plate I refer, of course, to those edges which extend longitudinally with respect to the length of the hose supported web 10.

I have found, however, that if the hose supporter plate is made of convex form in a transverse direction, that is, curved from the left-hand side to the right-hand side, as shown in Fig. 5, the side edges of the base will lie closely against the leg of the wearer. The button is secured upon the convex side of the plate so that the concave side thereof is toward the wearer's body, or downwardly facing with respect to the upper or outer face of the hose supporter.

As will be seen from Fig. 5, the base plate 17 is substantially straight in central longitudinal cross section. This is substantially the highest point of the plate, the latter being of arcuate shape in transverse cross-section, and in transverse elevation, as shown, for example, in Fig. 3.

When the plate is of this shape it is sufficiently round along its transverse dimension to conform to the rounding of the wearer's leg and lie closely thereto, particularly at its side edges, and these edges turn downwardly to a sufficient extent so that they do not tend to cut into the stocking which lies thereabove and is stretched thereover.

It will also be found that it is easier to secure the hose supporter grip to the stocking when the base plate is formed as illustrated herein. When the stocking is brought over the button and over the base plate and the button is threaded through the loop 12, this button will first enter the upper wider part of the loop. When the base plate is flat, the sides of the loop will contact therewith, and as the base plate holds the stocking in an outward position, it is sometimes difficult to slip the loop over the button unless the shank 14 is relatively long. In the present invention, when the side edges of the plate curve downwardly this will permit the side portions of the loop 12 to assume a lower position and permit an easy positioning of the button in the loop. The shank 14 can, therefore, be made shorter than the usual shank. This is quite advantageous in that the button does not project outwardly as far as with a longer shank, so as to make an undesirable protuberance in the clothing of the user, in addition, of course, to providing for an easier securing of the stocking, as heretofore explained.

It will also be noted that as the fabric 21 is brought upwardly around the lower edge of the slot 18, this rounded edge of the loop will, when

the shank is short, form a stop to prevent the loop 12 moving downwardly with respect to the button, as shown in Fig. 1, and thus becoming unfastened. The lower portion 13 of the loop may, therefore, be made with substantially parallel sides instead of being provided with a narrower throat, as is sometimes done to prevent the button slipping upwardly in the loop. This provision of parallel sides upon the loop portion 13 also provides for an easier securing of the grip to the stocking. 10

While I have shown and described a preferred embodiment of my invention, it will be understood that it is not to be limited to all of the details shown, but is capable of modification and variation within the spirit of the invention and 15 within the scope of the appended claims.

What I claim is:

1. In an attaching means for hose supporters or the like having a loop and a suitably supported button designed to be engaged with the loop, a 20 base plate upon which the button is mounted, said base plate having its side edges turned downwardly away from the button.

2. In an attaching means for hose supporters or the like having a loop and a suitably supported button designed to be engaged with the loop, a 25 base plate upon which the button is mounted, said base plate being convexly curved transversely of the loop whereby its side edges are at a lower level with respect to the button than its central 30 portion.

3. In an attaching means for hose supporters or the like having a loop and a suitably supported button designed to be engaged with the loop, a 35 base plate upon which the button is mounted, said base plate being of arcuate shape in transverse cross section and said button being mounted on the convex side of the plate.

4. In an attaching means for hose supporters or the like having a loop and a suitably supported button designed to be engaged with the loop, a 40 base plate upon which the button is mounted, said base plate being formed of relatively thin sheet metal and being of concavo-convex shape transversely of the longitudinal dimension of the hose 45 supported, and said button being mounted upon the convex side of the plate.

IRVING R. VERSOY.
